WRINGER

Frank Breckenridge, Mansfield, Ohio, assignor to
Westinghouse Electric & Manufacturing Company, East Pittsburgh, Pa., a corporation of Pennsylvania

Application May 23, 1939, Serial No. 275,163

10 Claims. (Cl. 68—249)

My invention relates to washing machine wringers and more particularly to an automatic tilting drainboard and guard mechanism operatively associated with the lower wringer roll thereof.

With the wringers now known that utilize a guard member or clothes-feeding device, it has been customary, in some instances, to have such member or device removably attached to the wringer frame. With such a removable structure, it has been necessary to move the device from side to side, depending upon which side an operator desires to use in feeding clothes into the wringer. It has likewise been necessary to remove such guard from the wringer when the operator desires to insert therein a large or heavy load, such as a quilt or the like. In addition, with those wringers having drainboards operatively associated with the lower or power roll, such drainboards have usually been located within the wringer frame in such a manner that they function primarily as a drainboard only. With those drainboards not associated with the lower or power roll it is necessary that the operator check the position of the drain before operating the wringer and to manually reverse the position of such drain upon reversing the direction of operation of the wringer.

It is, therefore, an object of my invention to provide a combination automatic tilting guard member, clothes feeder and drainboard which will permit the operator to insert any desired thickness of clothes between the wringer rolls while at the same time functioning as a guard and drainboard, and which will automatically tilt or change its position with the reversal of the direction of rotation of the rolls and function the same on either side of the wringer.

A further object of my invention is to provide an inexpensive, rugged unitary member which may be attached to the lower wringer roll to function as a combination guard member, feeding device and drainboard and be adapted to change its position with the reversing of rotation of the wringer rolls.

A further object of my invention is to provide an automatic locking means which will positively hold the combination device in the correct operating position during the wringing operations, and which will permit the device to reverse its position with the reversed rotation of the wringer rolls.

A still further object of my invention is to provide a delayed reversing action of the combination device which will permit the water to drain

out of the trough portion of the device before the reversing action of the device takes place.

Another object of my invention is to provide an automatic locking device for the combination device which will prevent the turning moment produced by the weight of heavy clothes, or the like, as they pass through the wringer, from rotating the combination device.

Other objects of my invention will either be pointed out specifically in the course of the following description of a device embodying my invention, or will be apparent from such description.

Referring to the accompanying sheets of drawings,

Fig. 1 is a top plan view of a wringer embodying my invention,

Fig. 2 is a side elevational view of the device shown in Fig. 1,

Fig. 3 is an enlarged sectional view taken along the line III—III of Fig. 2;

Fig. 4 is a partial side elevation and fragmentary view of the combination clothes feeder and collector, guard and water drain device showing its relationship with the lower wringer roll in an arbitrary neutral position;

Fig. 5 is a partial top view of one end of the wringer with the top cover and upper roll removed, showing the combination device and lower roll in an arbitrary neutral position;

Fig. 6 is a partial sectional view taken along the line VI—VI of Fig. 5;

Fig. 7 is a view similar to Fig. 3 showing a modified form of device embodying my invention;

Fig. 8 is a partial elevational and sectional view of a locking device embodying my invention;

Fig. 9 is a view taken along the line IX—IX of Fig. 8; and

Fig. 10 and 11 are side and end elevational views, respectively, of the locking member embodying my invention.

Referring to the accompanying drawings, I show a wringer 10, having a frame 14, transmission housings 18, lower and upper wringer rolls 66 and 68, respectively, a combination clothes feeder and collector, guard, and water drain device 48 operatively associated with lower roll 66, and a locking device 51 operatively associated with the lower wringer roll 66 and combination device 48 to delay the reversal and to prevent any backward rotation of the combination device due to the weight of clothes or the like.

The combination device 48 is herein shown as a part of a wringer more clearly described in

my copending application, Serial No. 288,311, filed August 4, 1939. However, it is to be understood that the combination device hereinafter described may be a separate entity which may be used on any desired wringer as well as on the one shown and described.

The combination deflector or drain, guard member, and clothes feeder and collector 48 comprises an upper elongated inwardly sloping hollow dished member 572 and a lower trough-shaped member 574 as shown in Figs. 3, 4 and 5. The upper inwardly sloped dished member 572 has an outwardly and upwardly extending ear portion 576 at both ends integral therewith and has an inwardly disposed flanged portion 578 along the lower longitudinal edge thereof to facilitate the cooperation of the upper member 572 and the lower member 574. The lower member 574 has the side bottom surfaces thereof tapered slightly toward the longitudinal center thereof and has a longitudinally slotted aperture 580 located in substantially the center of the bottom portion. The upper member 572 and the bottom member 574 have cooperating half collar portions 582 located at each end thereof, which cooperate with a split sleeve bearing 584 to support the device 48 upon the lower wringer roll 66. The lower trough-shaped member 574 is located about the bottom portion of the lower wringer roll 66 with the upper hollow dished member 572 placed upon the lower member and along-side of the lower roll, while the collar portions 582 thereof are associated with the slotted or split sleeve bearings 584.

As the top member 572 is placed upon the lower member 574, the inwardly flanged portions 578 of the top member 572 slides or fits within the upper edge of the lower member 574, forming a uniform functionally integral structure therewith. The collars 582, integral with the upper member 572, are at the same time positioned upon the split sleeve bearings 584. A plurality of bolts 586 are then inserted through the collar portions 582 of the upper and lower members 572 and 574, respectively, and are held together by means of nuts 588 (see Figs. 4 and 6). If desired, a resilient member 590 may be located between the head of the bolt 586 and the collar 582. As the nuts 588 are tightened upon the bolts 586, the resilient member 590 is compressed drawing the top member 572 into engagement with the bottom one. The collars 582 are thus tightened against the split sleeve bearings 584, causing the sleeve bearings to be drawn snugly against the wringer roll shaft 186.

With such an assembly of the device 48, in which the sleeve bearings are tightened upon the roll shaft 186 by the pressure supplied by the collars 582, it is apparent that, as the roll shaft 186 rotates in either direction, the device 48 will be rotated in the same direction. Then as the direction of rotation of the wringer roll is reversed, the combination device 48 will be rotated in the opposite direction. As the combination device rotates with and about the lower wringer roll 66 as an axis, the ears 576 contact a portion of the wringer frame 14, say at 638, as shown in Fig. 6 so as to limit the amount of rotation by the device 48. However, due to the relatively loose fit between the split sleeve bearing 584 and the shaft 186, the limitation of rotation of device 48 will not retard the rotation of the lower wringer roll 66. When the roll 66 and shaft 186 are rotated in a reverse direction, the combination device 48 will rotate with the shaft

186 until it is again stopped in rotation by contact with the wringer frame 14.

It is, therefore, obvious that the functionally integral combination device 48 comprising a guard member portion, clothes feeder and chute, and tilting drain-board portion, will automatically change its position from side to side depending upon the rotation of the wringer rolls, and, accordingly will always assume the correct operating position without any attention from the operator.

With the combination device 48 located in the position shown in Fig. 3, the right side of the device is substantially raised in contrast to the opposite side, which is substantially lowered. The right longitudinal edge or portion 592 of the top member 572, as shown in Fig. 3 is raised and is substantially in line with the line of contact of the two rolls of the wringer. In contrast with the raised right-hand edge, the left longitudinal edge or the portion 594 of the top member 572, located on the opposite side of the rolls, is lowered or substantially in line with the central portion of the drain shields 50. With the combination device 48 located in such a manner, and the lower wringer roll rotated in a counterclockwise direction, clothes are fed from the right side of the wringer as shown by the arrow A in Fig. 3, resting upon one of the drain shields 50.

With the portion 592 raised in such a manner, the inwardly extending top surface of the portion 592 may function as a clothes feeding chute. The clothes may be dropped over or placed upon the top of the raised portion 592 of the combination device 48, permitting such clothes to slide down the top surface 596 thereof as a feeding device. The clothes will thus encounter the lower wringer roll which will convey them through the wringer.

As the clothes are forced through the wringer rolls, by the rotation of such rolls, the inwardly sloping top surface 598 of the portion 594, being in a lowered or substantially horizontal position, functions as a clothes collector.

In other words, the clothes being forced through the wringer rolls will drop down upon the surface 598 which guides them out and down the main clothes chute 50. In addition to functioning in such a manner as a clothes collector, the inner edge of the portion 594 prevents clothes from sticking to the lower wringer roll 66.

As the portion 592 of the top member 572 is in a raised position, as hereinabove described, the portion of the combination device 48 extending above the central part 50 of the drain shield also functions as a guard member, preventing the entrance of the operator's hand directly into the wringer rolls. It is, therefore, obvious that when the portion 592 is in a raised position the combination device 48 functions on the feeding side of the wringer as a guard for the operator's fingers and as a clothes feeder, whereas that portion of the combination device located on the opposite side of the wringer functions as a clothes collector and prevents such clothes from wrapping on the lower roll.

In addition, as the clothes are fed into and between the wringer rolls 66 and 68, the excess moisture which is squeezed out of the clothes, such as washing water or liquid, runs down the right side of the lower wringer roll onto the inner surface of the bottom member 574 of the combination device 48. As the water proceeds into the bottom member 574, it falls from the

wringer roll, contacting the upper surface 600 of the right-hand portion 602 of the lower member 574. As the water strikes the surface 600, it is conveyed inwardly and downwardly to the transversely slotted aperture 580 where it drains out of the combination device onto the water drain member 70.

It is, therefore, apparent that with the combination device rotated in a counterclockwise direction, as shown in Fig. 3 and hereinabove described, the top surface 600 of the raised portion 602 of the lower member 574 functions as a water deflector, in addition to the hereinabove-mentioned functions of the combination device 48.

Should the lower wringer roll be rotated in an opposite or clockwise direction, the combination device 48 will, due to the friction engagement between the lower wringer drive shaft 186 and the split bearing 584, likewise be rotated in a clockwise direction until the ear 576 strikes the frame at 638, as shown in Fig. 6. With the combination device located in such a manner, the left-hand portion 594 of the upper member 572, as seen in Fig. 3 will be in a raised or feeding and guard position while the portion 592 will be in a lower or clothes collecting position. The top surface 598 of the portion 594 will then function as a clothes feeder permitting the clothes to be automatically fed to the wringer rolls, whereas the top surface 596 of the portion 592 will function as a clothes collector, preventing such clothes from wrapping around the wringer rolls. The raised portion 594 will also function as a guard member protecting the operator's fingers and preventing their entrance into the wringer rolls as hereinabove described. The top surface 604 of the left-hand portion 606 of the lower member 574 of the combination device 48 will then function as a water deflector directing the water being squeezed out of the moist clothes down through the transversely slotted aperture 580 and upon the water drain member 70 in a manner as hereinabove described.

It is, therefore, obvious that due to the operation of the collars 582 with the slotted or split sleeve bearing 584 upon the lower wringer shaft 186, such combination device 48 will automatically reverse its rotation depending upon the rotation of the wringer itself. It is further obvious that, with the combination device 48 rotated into the proper working position as hereinbefore described, such device will function simultaneously as a guard member, an automatic clothes feeding device, a clothes collector and a water deflector for deflecting the water upon the proper side of a fixed water drain member 70, and that with the reversal of rotation of the wringer such combination device 48 will function in a similar manner deflecting the water upon the opposite side of the stationary water drain member 70.

A modified combination water deflector device 49 may be built substantially as shown in Fig. 7, which comprises a plurality of elongated hollow quarter-cylinder members 608 and 610 which serve as the guard member, clothes feeder and clothes collector, and a separate independent rockably mounted water deflector member 612. The members 608 and 610 are separate integral pieces attached to the lower wringer roll shaft 186 by means of a plurality of collars (not shown), which in this instance are attached to the members 608 and 610, substantially in a manner as hereinabove described. The member 608 is located about one side of the wringer

roll, while the member 610 is located about the other side. The lower portions 608 and 610 are joined at the ends thereof by substantially U-shaped strap-type operating members 614. An elongated aperture 616 is thus positioned between the lower inner edges of the members 608 and 610. The rockably mounted drain member 612 is mounted upon suitable boss portions 634 protruding upwardly from the central portion 10 of the drain member 70, or in any other suitable manner. The rockably mounted water deflector member 612 has an upstanding end portion 618 with a protuberance 620 located in the uppermost portion thereof to cooperate with the U-shaped members 614. The cooperation between the protuberance 620 and U-shaped member 614 results in the rockably mounted water deflector 612 rotating in an opposite direction to the main combination device. This action ensures that the moisture, from the clothes being run through the wringer, will always be automatically directed in the proper direction.

The members 608 and 610 forming the combination device 49 have upward extending portions 622 and 624, respectively, which function in a manner substantially as the portions 592 and 594 of the preferred device 48; that is, the portion 622 on the upper surface of the inclined plate 626 functions as a clothes feeder, while the outer 20 surface of the portion 622 functions as a guard member, and at the same time, the portion 624 is lowered so that the upper surface 628 thereof functions as a clothes collector. The top inner surface of the lower portions of members 608 and 610, respectively, directs the water squeezed from the wet clothes downwardly and through the elongated aperture 616. As the water falls through the aperture 616, it strikes the oscillatable independent water deflector member 612 which automatically directs such water down the proper side of the water drain member 70.

It is, therefore, obvious that, inasmuch as the combination device 49 is operatively associated with the lower wringer shaft 186 in substantially the same manner as the combination device 48, such device will reverse its position with any change in rotation of the wringer rolls, substantially as hereinabove described. With the combination device 49 adapted to be rotated in such a manner, the combination device 49 will function simultaneously as a guard, clothes feeder and a clothes collector. In addition when the rockable water deflector member 612 is operatively associated with such combination device, it is obvious that such drain member will assure the proper flow of the water down the drain member.

The locking device 51 operatively associated with the combination device 48 (see Figs. 8, 9, 10 and 11), comprises a lever 700, a Y-shaped arm 60 702 which cooperates with the lever 700 and the lower portion 574 of combination device 48. The lever or arm 700 is, in this instance, an elongated piece of sheet metal folded back so as to cooperate with the shaft 186 of the lower wringer roll. The arm 700 is operatively associated with the shaft 186 by being placed over and tightened against a split bearing 706 by means of a suitable screw 707. A resilient member 705 may be positioned between the head of the set screw and the arm 700 to produce a biasing action therebetween. This action permits the arm 700 to rotate with the shaft 186 and the split bearing 706 and permits the arm 700 to remain stationary while the shaft 186 and bearing 706 rotates.

The Y-shaped lever 702 is attached to the wringer frame by being rockably or rotatably attached by means of an angular bracket 714 to a protuberance 718 which is integral with the wringer frame. The arm 702 is attached to the bracket 714 by means of a suitable rivet 712, while the bracket 714 is rigidly attached to the protuberance 718 by means of a suitable screw 716. The Y-shaped arm 702 has a plurality of outwardly extending lugs 708, 709, 710 and 711 which extend substantially normal to the plane thereof. The lugs 708 and 709 are located at the upper end of the respective arms of the lever 702 and extend toward the protuberance 718 or away from the combination device 48. The lugs 710 and 711 are located substantially at the lower end of the arms of the lever 702 and extend inwardly or toward the combination device 48 to cooperate with such device 48 so as to limit its rotation, as hereinafter described.

The combination device 48 has an inwardly extending concavity 704 which is positioned substantially in the lower central portion of the combination device (see Figs. 8 and 9). The concavity 704 is adapted to cooperate with the inwardly extending lugs 710 and 711 of the arm 702 to prevent any undesirable movement of the device 48 and to lock such device in either working position.

The arm 700 rotatably attached to the lower wringer drive shaft 186, as hereinabove described, is adapted to cooperate with the outwardly extending lugs 708 and 709. Assuming that the lower wringer roll is to rotate in a counterclockwise direction, as shown in Fig. 9, such arm will move the lug 708 upwardly causing the arm 702 to be likewise rotated in a counterclockwise direction. This action causes the inwardly extending lug 710 to be raised or moved into the concavity 704, so as to limit the rotation of the device 48.

With the lower wringer rolls 66 rotating in a counterclockwise direction (see Fig. 9), the combination device 48, due to the friction drive between the lower wringer roll shaft 186 and sleeve 584, will also be rotated in a counterclockwise direction and the right portion 592 thereof will be raised. The device 48 will then be prevented from rotating in a clockwise direction due to the cooperation of such device with the locking device 51. The arm 700 is rotated in a counterclockwise direction with the roll shaft 186 and the arm 702 will thus be moved in a counterclockwise direction and the inwardly extending lug 710 will be moved up into the concavity 704. The cooperative action of arms 700 and 702 will thus maintain the lug 710 within the concavity 704 in the device 48.

It, therefore, follows that the inwardly extending lug 710 will remain within the concavity 704 as long as the lower wringer roll runs in a counterclockwise direction, and, that, due to such cooperation, the combination device 48 cannot be forced in a clockwise direction. It further follows that regardless of the load being fed in through the wringer and resting upon the raised portion 592 of the combination device 48 or the amount of downward pressure applied by an operator, the combination device 48 will be retained in its present position. In addition to being maintained in the present position during the operation of the wringer, such device will remain in that position, permitting any water or moisture in the device 48 to run out and down

the water drain 70, a short time after the rolls are reversed, as hereinafter described.

Should it be desired to operate the wringer in a reverse direction, the lower wringer rolls would rotate in a clockwise direction. The arm 700 would then simultaneously rotate in a clockwise direction for about 90° or until it contacted the outwardly extending lug 709, forcing the arm 702 in a clockwise direction. This cooperation would then cause the arm 702 to be rotated in a clockwise direction, causing the inwardly extending lug 710 to be removed from the concavity 704. The combination device 48, due to the frictional engagement with the split bearing 584 as hereinabove described, will then be free to rotate in a counterclockwise direction until it is stopped, due to its cooperation with the wringer frame 16. When the combination device is rotated in a clockwise direction to its second operating position, the cooperation of arm 700 with lug 709 and arm 702 will then cause the arm 702 to rotate a short distance further in a clockwise direction. The inwardly extending lug 711 would then extend into the concavity 704, locking the device in the new position.

It follows that due to the cooperative action between the arms 700 and 702, the combination device 48 will remain in its original position during the time the arm 700 moves from one position to another immediately after the direction of rotation of the rolls is changed. This lag in movement between the time the direction of rotation of the rolls is changed and the time the combination device 48 starts to change its position results in a delayed reversing action of the combination device, which permits any water therein to drain out before the reversing action of the device takes place. It is, therefore, obvious that the combination device 48 will function as an automatic tilting clothes feeder and chute guard member and drain member and that due to the cooperation of the locking device therewith such combination device can only be rotated in response to the lower roll shaft and with a delayed action thereof.

Various further modifications may be made in the device embodying my invention without departing from the spirit and scope thereof, and I desire, therefore, that only such limitations shall be placed thereon as are imposed by the prior art and the appended claims.

I claim as my invention:

1. In a reversible wringer having a frame and a plurality of rolls one above the other, an elongated inwardly flanged unitary channel shaped device mounted about the lower roll only and movable with respect to the frame and lower roll embodying a portion on each side of the wringer, each of which at one time serves as a guard, clothes feeder and water deflector, and at another time as a collector for the clothes, and means whereby when the channel shaped device is operatively adjusted with the lower roll, the portion which is to serve as a guard, clothes feed and water deflector is elevated and the portion which is to serve as a clothes collector is lowered, at least a part of the guard and feed portion extending in front of the rolls.

2. In a reversible wringer having a frame and a plurality of rolls one above the other, an elongated inwardly flanged unitary channel shaped device mounted about the lower roll and movable with respect to the frame and lower roll embodying a portion on each side of the wringer, each of which at one time serves as a guard and

water deflector and at another time as a clothes chute, and means whereby when the channel shaped device is operatively adjusted, the portion which is to serve as a guard and water deflector is elevated and the portion which is to serve as a clothes chute is lowered, at least a part of said water deflector portion extending in front of and below the lower roll.

3. In a clothes wringer, the combination of a frame, rolls therein, an elongated inwardly flanged unitary channel shaped device coaxially mounted with respect to one of said rolls embodying a deflector portion which may be adjusted to direct the flow of water coming from the rolls and guard portions for protecting an operator from the rolls, and means whereby when the deflector is properly adjusted for a given rotation of the wringer the guard which is to protect the operator is elevated and positioned in front of said rolls, said deflector portion having at least a part thereof in front of and below said lower roll.

4. In a clothes wringer, the combination of a frame, an upper and lower roll therein, an elongated inwardly flanged unitary channel shaped device coaxially mounted with respect to one of said rolls embodying a deflector portion which may be adjusted to direct the flow of water coming from the rolls in either direction and a clothes feeder for feeding clothes to the rolls, and means whereby when the deflector is properly adjusted for a given rotation of the rolls, the clothes feeder which is to feed clothes to the rolls is elevated with at least a part thereof extending in front of said rolls and having a surface which converges toward the lower roll to provide a feeding trough.

5. In a clothes wringer, the combination of a frame, rolls therein, an elongated inwardly flanged unitary channel shaped device coaxially mounted with respect to one of said rolls embodying a deflector portion which may be adjusted to direct water coming from the rolls in either direction and clothes feeder portions for feeding clothes to the rolls, and means whereby when the deflector is operatively adjusted for a given rotation of the rolls, the clothes feeder portion which is to feed clothes to the rolls is elevated with at least a part thereof extending in front of said rolls and having a surface which converges toward the lower roll to provide a feeding trough, while the second clothes feeder portion is lowered to serve as a clothes collector for preventing clothes from sticking to the lower roll.

6. In a reversible wringer, a plurality of rolls, an elongated inwardly flanged unitary channel shaped device coaxially mounted with respect to one of said rolls comprising a portion on each side of the wringer, each of which at one time serves as a guard and at another time as a collector for clothes which prevents clothes from sticking to the lower roll, and means whereby when the device is adjusted in one position the portion which is to serve as a guard member is elevated and the portion which is to serve as a

clothes collector is lowered, said guard member portion being positioned in front of the rolls, said guard member having a portion constituting the only clothes feeder in the wringer.

7. In a reversible wringer having a frame and a plurality of rolls one above the other, an elongated inwardly flanged channel shaped device mounted about the lower roll and movable with respect to the frame and lower roll embodying a portion on each side of the wringer, each of which at one time serves as a clothes feeder and guard member and at another time as a collector for clothes which prevents clothes from sticking to the lower roll, and means whereby when the device is adjusted in one position the portion which is to serve as a clothes feeder and guard member is elevated with at least a part thereof extending in front of the rolls and the portion which is to serve as a clothes collector is lowered, said clothes feeder constituting the only feeder in the wringer.

8. In a reversible wringer, a frame, a plurality of rolls one above the other, an elongated inwardly flanged channel shaped device embodying guard, water deflector, clothes collector and feeder portions positioned about and operatively associated with the lower roll and movable with respect to the lower roll and frame, and a locking device attached to the frame and operatively associated with the lower roll and channel shaped device for automatically locking the channel shaped device in either of two working positions.

9. In a reversible wringer, a frame, a plurality of rolls one above the other, an elongated inwardly flanged channel shaped device embodying guard, water deflector, clothes collector and feeder portions positioned about and operatively associated with the lower roll and movable with respect to the lower roll and frame, and a locking device attached to the frame and operatively associated with the lower roll and channel shaped device for automatically locking the channel shaped device in either of two working positions and for delaying the reversing action of the channel shaped device upon reversing the rotation of such lower roll.

10. In a reversible wringer having a frame and a plurality of rolls one above the other, an elongated inwardly flanged unitary channel shaped device mounted about the lower roll only and movable with respect to the frame and lower roll embodying a portion on each side of the wringer, each of which at one time serves as a guard, clothes feeder and water deflector, and at another time as a collector for the clothes, and means whereby when the channel shaped device is operatively adjusted, the portion which is to serve as a guard, clothes feed and water deflector is elevated and the portion which is to serve as a clothes collector is lowered, the upper edge of each of said portions when serving as a guard lying in a plane which is substantially tangent to both rolls at the bite.

FRANK BRECKENRIDGE.
